UNITED STATES PATENT OFFICE.

JENS CHRISTIAN JENSEN AND ORVILLE LEIGHROY MILES, OF CHICAGO, ILLINOIS;
SAID JENSEN ASSIGNOR TO SAID MILES.

ARTICLE-DISPENSING DEVICE.

Application filed January 25, 1924. Serial No. 688,483.

Our invention relates to article dispensing devices, and more particularly to a dispensing device operating in conjunction with a coin controlled device.

5 Heretofore the articles or packages dispensed by the usual coin controlled dispensing machine had to be stacked in a row in the article containing compartment, or arranged in some orderly manner therein in 10 order that the machine may properly dispense said articles; and such stacking and arranging of the articles in said compartment required considerable time.

15 It is our object to provide such a dispensing machine having a compartment or container into which the articles or packages may be dumped or placed at random and without being arranged in any particular order therein; and to provide means in said 20 machine for taking said articles or packages and arranging and delivering them in the desired proper manner. A further object is to provide such a machine which is operated by means of a coin controlled device and is 25 arranged to deliver said articles or packages in harmony with the operation of said coin controlled device.

30 It is to be understood that the terms "articles" and "packages", as used in this application, are meant to include a single piece of gum, candy, or the like, or likewise several things or pieces thereof combined by the use of a wrapper or binding means into a single package or article.

35 Other objects will appear hereinafter.

The invention consists in the combinations and arrangements of parts hereinafter described and claimed.

40 The invention will be best understood by reference to the accompanying drawings forming a part of this specification, and in which,

Fig. 1 is an elevational view of a housing comprising an embodiment of our invention;

45 Fig. 2 is a slightly enlarged vertical section of said invention, taken on line 2—2 of Fig. 1;

50 Figs. 3 and 4 are horizontal sections thereof, taken on lines 3—3 and 4—4, respectively, of Fig. 2;

Fig. 5 is a partial vertical section, taken on line 5—5 of Fig. 2;

Fig. 6 is an inverted horizontal section on line 6—6 of Fig. 5;

Fig. 7 is a horizontal section on line 7—7 of Fig. 2;

Fig. 8 is an enlarged plan view of the pinion and oscillating means, shown inverted in Fig. 6;

Fig. 9 is a vertical section on line 9—9 of Fig. 8; and

Fig. 10 is a vertical section on line 10—10 of Fig. 3.

In the drawings we have disclosed the preferred form of construction for carrying our invention into effect, and said form comprises a housing 12 having an upper compartment or container 13 provided therein for receiving the articles or packages, which may be dumped or placed therein at random and without being arranged in special order. An openable cover or top 14 is mounted on the open upper end of said compartment, and is preferably provided with flanges 14' to slidably engage beneath the upper rim 12' of the housing, locking means 15 being provided to lock the cover in position. Windows 16 are preferably provided at the front and sides of the compartment 13, and windows 17 are preferably placed in sides and front of the cover 14, an electric light 18 being mounted in the cover to illuminate the device.

A casing 20, preferably cylindrical in form, is mounted with upwardly inclined flanges 20' in said housing, said flanges forming part of the bottom for the compartment 13. A shaft 21 is mounted to rotate in the bottom 22 of said casing, and a member

23, preferably cylindrical in form, and having a dome shaped top is secured to the top of said shaft to rotate therewith. One or more stirring elements or arms 24 are mounted on the top of said member for stirring

and moving the articles as the member rotates and in order to slide them into the space 25 formed between the circumference of said member and the inner wall of casing 20. The member 23 with its arms 24 forms

means for stirring and moving the packages downward from the container and primarily arranging the same in order, the size of the space 25 being arranged to suit the thickness and height of an article or package dispensed by said machine.

We provide means for further arranging and for feeding the articles, such means comprising a member 26, preferably cylindrical

100

105

in form, which is provided with an upper horizontal flange 27 extending partly around said member, and a pair of inclined flanges 28 and 28' slanting downward in opposite directions from flange 27 around the member 26, and having the lower parts 29 bent vertically downward forming a space or gate 30 therebetween, which is of the size of an article or package to be fed therethrough, 10 and flanges 31 extend from the lower end of said flanges 29 horizontally around the bottom of cylindrical member 26 and serve to prevent articles or packages which have been fed through space or gate 30 from moving upwards.

The means for operating the feeding mechanism comprises a gear 32 fastened on shaft 21 (Figs. 5 and 6) and engaging a pinion 33 having a disc 34 thereon with a 20 pin 35 which engages in a slot 36 in an arm 37 fastened on a diaphragm 38 provided in the lower part of cylindrical member 26, said pinion 33 being pivoted on a lower wall 39 of casing 20. The rotation of shaft 21, 25 oscillates said feeding mechanism and arranges the articles between cylindrical member 26 and casing 20, above the inclined flange 28, and with such oscillation the packages slide down into space 30; the space 30 beneath the upper flange 27 and the inclined flange 28' therebeneath being provided to receive articles only when descending too rapidly on the opposite inclined flange 28, and thus provides elasticity to the feeding 35 mechanism and prevents overcrowding or blocking of the articles when moving from said opposite flange 28 into said space 30, and when the articles move too slowly down the flange 28 then the articles on flange 28' 40 will move forward into space 30.

We provide means for delivering the articles received from said feeding means, said delivering means including means for containing a plurality or a row of articles arranged in order, also means for resiliently moving or shoving said plurality or row of articles toward the discharge opening, and means for properly timing and discharging said articles. The means for containing 45 said row comprises a cylindrical member 40 extending upward from the lower end of casing 20 to the wall 39 which forms its top, an annular channel 41 being formed between said member 40 and casing 20, beneath flange 31, for housing a row or plurality of said articles to enable them to be fed promptly without interruption and in proper order. The means for moving or shoving 50 said articles forward in close formation comprises a plurality of spaced arms 42 resiliently mounted as with coil springs 43, on the perimeter of a drum 44 which is fastened with its ends on the shaft 21 to rotate therewith, said arms extending into 55 said channel 41, through slots 45 formed in

cylindrical member 40, and travel in the direction of the arrow shown in Fig. 4. A bar 46 extends from flange 31 into space 41 (see Figs. 2 and 10), beneath flange 28' and adjacent space 30 to prevent articles from 60 moving backward, and said arms 42 swing backward on springs 43 when they engage edge 40' of member 40 during their forward travel.

The discharge and timing means 75 comprises a companion pair of partial cylindrical members 47 and 48 pivotally mounted between members 22 and 39, in the delivery end of channel 41 (see Figs. 4 and 5), said members being spaced so as to prevent resilient arms 43 from forcing articles or packages therethrough, and intermeshing gear sectors 47' and 48' are provided on members 47 and 48 to rotate them together and to force the articles therewith out of 80 said channel. A slotted link 49 is fastened to a shaft 50 depending from member 47, and a crank arm 51 is mounted on main shaft 21, carrying a pin 52 which slides in the slot in said link 49 to operate said gear 85 sectors and cylindrical members; the construction being so arranged as to oscillate said partial cylindrical members 47 and 48 just sufficiently with each revolution of the main shaft 21 to grasp one article from 90 channel 41 and force it outward therebetween, into a discharge spout 53 to slide and deliver the article out of the device.

This dispensing device is particularly arranged to cooperate with a known and suitable type of coin controlled mechanism 55 having the usual coin receiving slot 56 and an operating shaft with a hand wheel 58, which is turnable when the proper coin has been deposited in slot 56. To the inner end of 100 this operating shaft 57 is fastened a pinion 59 in position to engage a pinion 60 fastened on the main shaft 21 of the dispensing device. The pinions 59 and 60 are furnished in comparative sizes to rotate said main shaft 105 21 a complete revolution, to discharge an article or package with each individual operation or turn of the coin controlled shaft 57 permitted in consequence of the particular coin deposited.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the 110 scope of the appended claims.

Having described our invention, what we claim as new and desire to secure by Letters Patent is:

1. A dispensing device comprising a casing; a hopper in said casing; a rotatable 130

space around said arranging member; a horizontal flange extending around a portion of the top of said arranging member; an inclined flange extending around the body of said arranging member, there being a discharge space at the lower end of said inclined flange, under said horizontal flange; a horizontal flange extending from the sides of said discharge space around said arranging member; an oscillatory connection between said shaft and arranging member for oscillating the latter; a stationary member under said arranging member forming an annular discharge space registering with the said discharge space of said arranging member; a plurality of springheld fingers mounted upon and radiating from said shaft, there being slots in the wall of said stationary member permitting the protrusion of said fingers to move articles in said annular discharge space; a companion pair of partially cylindrical members arranged at the delivery end of said discharge space; interrupted gear members operating said partially cylindrical members to discharge the end-most article from said annular discharge space;

and an operative connection between said shaft and said partially cylindrical members for oscillating the same to discharge the end-most member from said annular discharge space, substantially as described.

9. A dispensing device comprising an annular feed chamber having horizontal slots in one wall; a plurality of yielding fingers projecting through said slots into said chamber and traveling through said chamber; and means for discharging the end-most article from said chamber, substantially as described.

10. A dispensing device comprising an annular feed chamber having slots in its inner wall; a plurality of revolving yieldable fingers arranged within the inner wall of said chamber and to project through said slots; and means for discharging the end-most article from said chamber, substantially as described.

In testimony whereof we have signed our names to this specification.

JENS CHRISTIAN JENSEN.
ORVILLE LEIGHROY MILES.
